US0D1086458S

(12) **United States Design Patent** (10) **Patent No.:** **US D1,086,458 S**
(45) **Date of Patent:** **** Jul. 29, 2025**

(54) **MEDICAL DRILL**

(71) Applicant: **CUREXO INC.**, Seoul (KR)

(72) Inventors: **Changhun Lee**, Seoul (KR); **Kwanju Lee**, Seoul (KR)

(**) Term: **15 Years**

(21) Appl. No.: **35/520,601**

(22) Filed: **Apr. 14, 2023**

(80) **Hague Agreement Data**

Int. Filing Date: **Apr. 14, 2023**

Int. Reg. No.: **DM/231126**

Int. Reg. Date: **Apr. 14, 2023**

Int. Reg. Pub. Date: **Apr. 19, 2024**

(30) **Foreign Application Priority Data**

Nov. 4, 2022 (KR) 30-2022-0045521
